(57) **CLAIM**

The ornamental design for a cabinet door handle hasp, as
shown and described.

DESCRIPTION

FIG. 1 is an isometric view of the cabinet door handle hasp,
embodying the claimed design;

FIG. 2 is a right plan view thereof;

FIG. 3 is a left plan view thereof;

FIG. 4 is a front plan view thereof;

FIG. 5 is a rear plan view thereof;

FIG. 6 is a top-down plan view thereof; and,

FIG. 7 is a bottom-up plan view thereof.

The broken lines in the drawings depict portions of the
cabinet door handle hasp that form no part of the claimed
design.

1 Claim, 7 Drawing Sheets
